UNITED STATES PATENT OFFICE.

JACOB KOHN, OF NEW YORK, N. Y.

LOCK.

1,302,565.

Specification of Letters Patent.

Patented May 6, 1919.

Application filed December 11, 1917. Serial No. 206,678.

To all whom it may concern:

Be it known that I, JACOB KOHN, a citizen of the United States, and a resident of the borough of Manhattan, city and State of New York, have invented certain new and useful Improvements in Locks, of which the following is a specification.

My invention relates to locks for doors and the like and more particularly to that type of locks in which the bolt, instead of having sliding movements in linear directions, is movable to and from an operative position in the arc of a circle. The object of my invention is to provide a simple construction having a minimum number of parts and which operates with a maximum of efficiency to securely hold doors and the like against forcing or other unintentional opening. Other objects of my invention will appear in the description hereinafter and the features of novelty will be pointed out in the appended claims.

In the accompanying drawings which, for illustrative and descriptive purposes show an example of my invention, Figure 1 is an elevation showing my improved lock operatively combined with an inwardly swinging door; Fig. 2 is a sectional view on the line 2-2 of Fig. 1; Fig. 3 is a view similar to Fig. 1 with a portion of the lock casing removed to expose the interior; Fig. 4 is a view similar to Fig. 3 but illustrating the parts in different positions; Fig. 5 is a plan view of Fig. 4 with the door and door casing shown in section; Fig. 6 is an elevation of the front section of the lock casing; Fig. 7 is a plan view partly in section illustrating my improved lock operatively combined with an outwardly swinging door and Fig. 8 is a detail perspective view of a locking element forming part of my improved lock.

As shown in the illustrated example, my improved lock comprises a hollow, metallic or other casing 10 which may consist of a back plate 11 and a front section 12. The back plate 11 and the front section 12 may be provided respectively with a stud 13 and a boss 14 arranged in axial alinement, the boss 14 preferably being of somewhat larger external diameter than the stud 13, as shown

in Fig. 2. A screw 15 passes through an axial passage formed in the boss 14 into screw-threaded engagement with a screw-threaded aperture formed in the stud 13 and serves 55 to detachably connect the back plate 11 and front section 12 together. The back plate 11 is provided with suitable openings for the accommodation of screws or the like 16, whereby the lock is attached in operative 60 position upon the door or the like 17. Some of said screws may also pass through suitable openings in the casing section 12, thus providing an additional means whereby the back plate 11 and section 12 are combined. 65 A bolt 18 is pivotally mounted upon the stud 13 in engagement with the annular shoulder formed by the end face of the boss 14 which thus forms a bearing therefor, said bolt extending exteriorly beyond the casing 70 10 through a suitable opening 10^a therein, as shown in the drawings. If the lock is intended for use with a door opening inwardly in the direction indicated by the arrow in Fig. 5, the bolt 18 coöperates with a keeper 75 19 suitably secured to the door casing 20 by means of screws or the like 21 and including an upwardly open recess 22 for the accommodation of said bolt 18, as shown in Figs. 1, 3 and 5. In this case the free end of the 80 bolt 18, when in its locking position, preferably extends horizontally through the recess 22 and is provided with a transverse projection 23 which coöperates with the keeper to prevent any material separation 85 of the door and its casing at the opposed edges *a* and *b*. If, on the other hand, the lock is intended to be operatively combined with a door opening outwardly the transverse projection, at the free end of the bolt 90 18 is increased in length as indicated at 22^a to fit into the recess 22^a of the keeper 19^a. In other words, the latter, which may be of the same general construction as the keeper 19, is positioned on the door casing 20^a with 95 its recess 22^a extending in a direction at right angles to that of the recess 22 in Fig. 5. The transverse projection 23^a is further formed with a hook or member 23^b which extends substantially parallel with the bolt 100 18 and coöperates with said keeper 19^a to prevent the door 17^a from swinging out-

wardly upon its hinges. The transverse projection 23^a also serves to prevent any material separation of the door and casing at the opposed edges *a* and *b*. It will, of course, be obvious that the bolt 18 shown in Figs. 1 to 5 may also be effectively used in combination with an outwardly opening door and similarly that the bolt shown in Fig. 7 may be efficiently combined with a door opening inwardly if this should be desired. Both forms of bolts are further adapted for use in locking sliding doors against unintentional opening, as will be readily apparent.

Whether constructed to lock an inwardly or an outwardly opening door, or a sliding door, the bolt 18 in either case is formed at its inner end portion with a depending extension 24 in which an outwardly open slot 25 is formed, said slot being preferably inclined with respect to the bolt 18, as shown in Figs. 1, 3 and 4. The lock further includes a lever 26 carried by a sleeve 26^a rotatably mounted in the back plate 11 of the casing 10, said lever preferably being located in surface engagement with said back plate 11, as shown in Fig. 3, and arranged for connection with the customary key-operated mechanism whereby the lock is usually manipulated from the outside. For instance, said lever 26 and sleeve 26^a may be provided with an axial opening 27 of angular form and adapted to receive the end of a similarly formed connecting rod 28 whereby the tumbler barrel 29 of the key-operated mechanism is operatively connected with the lock. The barrel 29 may form an integral part of a key plate 30 located upon the outside surface of the door, which in this case is formed with a suitable aperture 31 for the accommodation of said tumbler barrel 29 in the well known way. Any suitable means may be employed for securing the tumbler barrel 29 and key plate 30 upon the door, as, for instance, screws 32 suitably connected with the lock and extending into screw-threaded engagement with lugs 33 formed, for instance, on the barrel 29. It will, of course, be understood that the lever 26 may be operatively connected with any other kind or type of key operated or other mechanism whereby the lock may be manipulated from the outside.

The lever 26 is provided with a transverse pin 34 adapted to enter the slot 25 and engage the depending extension 24 to swing the bolt 18 in a manner to be more fully described hereinafter, and is further formed at its free end with a preferably rounded nose 35, the purpose of which will also appear more fully further on in the description.

The lock may be actuated from the inside in any suitable manner as, for instance, by

means of a knob 36 journaled in the front section 12 of the casing 10 and having a reduced end 37 which extends through the same as shown in Fig. 2. The end 37 of the knob 36 carries a double lever 38 preferably located in surface engagement with the inner surface of the casing section 12 and provided at its opposite ends with pins 39, each of which is arranged to also enter the slot 25 for engagement with the extension 24 to actuate the bolt. The opposite ends of said double lever 38 are also formed with preferably rounded noses 40 similar to the nose 35 of the lever 26. A leaf spring 41 is secured in the casing 10 and is provided with a notch 42 for the reception of the pins 39 whereby the lever 38, in addition to being under the influence of said spring, is stopped in the position shown by dotted lines in Fig. 6.

A locking member 43 is pivoted at 44 upon the back plate 11 and extends between the latter and the bolt 18 as shown in Fig. 2, said member being formed with a transverse shoulder 45 adapted to coöperate with notches or the like 46 and 47 formed in a preferably curved edge 48 of the bolt 18 to lock the latter respectively in its operative and its inoperative positions. The member 43 is further provided with integral cams 49 and 50 located in spaced and preferably parallel relation to each other as illustrated in Fig. 8, said cams being arranged for coöperation respectively with the noses 35 and 40 of the levers 26 and 38 to release the bolt 18 from the shoulder 45, as will be more fully set forth hereinafter. The locking member 43 is under the influence of a spring 51 which exerts a tension tending to maintain the shoulder 45 in one or the other of the notches 46 and 47. A projecting finger 52 is also carried by the member 43 and has its free end arranged to enter a notch 53 formed on the lever 26 whereby the rotative movement of the latter in one direction is arrested, when the bolt 18 is in its operative position; it will, of course, be understood that the notch 53 may be omitted without materially interfering with the efficiency of the finger 52 as a stop. A similar finger 54 is located upon the inner end of the bolt 18 in proper position for engagement with a lug 55 on the lever 26 whereby the rotative movement of the latter, in the opposite direction is arrested, when the bolt 18 is in its inoperative position. A disarrangement of the parts is thus positively prevented with the construction described. If desired, a stud or pin 56 may project from the bolt 18 into engagement with the inner surface of the section 12 of the casing 10 for steadyng the bolt 18 in its movements against undesirable vibration.

In practice when the locking mechanism is

- in its operative position and the bolt 18 is located in the recess 22 or 22^a of the keeper 19 or 19^a as shown in Figs. 1, 3 and 7, the door 17 or 17^a is firmly and securely locked 5 against any movement on its hinges, or in the case of a sliding door, is firmly held against any sliding movement; at the same time, because of the coöperation of the transverse projections 23 and 23^a with the respective 10 keepers 19 and 19^a, it is absolutely impossible to bring about any material separation of the door edge *a* and edge *b* of the casing 20 or 20^a. It is thus substantially impossible, for instance, to successfully jimmy the door 15 or to break the operative connection between the bolt 18 and its keeper 19 or 19^a, as is clearly apparent in the drawings. It will be seen that the bolt 18 is securely locked against any swinging movement through the 20 coöperation of the shoulder 45 of the locking lever 43 and the notch 46, so that it is impossible to disconnect the bolt from its keeper by means of any instrument inserted between the door and its casing.
- 25 If the door, of whatever type it may be, is to be legitimately opened from the outside, the proper key 57 is inserted into the key hole of the key plate 30 and rotated in the usual way to bring about a rotation of the 30 connecting rod 28 and consequently a similar movement of the sleeve 26^a. As the latter is thus rotated, the lever 26 will be moved in the arc of a circle in the direction indicated by the arrows in Fig. 3 thus causing the pin 34 to enter the slot 25 of the bolt 18 and finally to bear against a wall of said slot or in other words against the extension 24. The 35 described actuation of the lever 26 also causes the nose 35 thereof to engage the cam 49 of the locking lever 43 whereby the latter is swung against the tension of the spring 51 to move the shoulder 45 out of the notch 46; the locking lever 43 is thus rendered ineffective as a means for preventing a swinging 40 movement of the bolt 18 toward its inoperative position. The engagement of the nose 35 with the cam 49 takes place before the pin 34 comes into contact with the extension 24 so that the bolt 18 is released in time to 45 permit its intended actuation by the lever 26 through the medium of the key actuated mechanism. As the operation of the latter is continued to completion, the rotation of the lever 26 will be also continued whereby 50 the pin 34 is caused to exert a pressure against the extension 24 and thus swing the bolt 18 upwardly in the opening 10^a and out of the recess 22 or 22^a of the keeper 19 or 19^a to the position shown in Fig. 4. During 55 the described movement of said bolt 18 the shoulder 45 will ride along the curved surface 48 of the extension 24 and, under the influence of the spring 51, will finally snap into the notch 47 whereby the bolt 18 is se- 60 curely held in the inoperative position shown in Fig. 4. In this condition of the parts the bolt and keeper are disengaged so that the door may be freely opened, it being understood, in all cases, that the parts are so constructed and located as to prevent any interference between the bolt in its inoperative position and the door casing, as the door is 65 opened and closed.
- To open the door from the inside the knob 36 is rotated, which movement is transmitted 70 to the double lever 38 and causes one of the pins 39 thereof to enter the slot 25 and to finally engage the extension 24. Prior to such engagement the coöperating nose 40 of said lever 38 will contact with the cam 50 75 and thus swing the lever 43 against the tension of the spring 51, whereby the shoulder 45 is moved out of the notch 46 and the bolt 18 released in the same manner as previously described. A continued actuation of the 80 knob 36 and lever 38 will swing the bolt 18 to the inoperative position shown in Fig. 4 in which, as before stated, it is locked by means of said shoulder 45 and notch 47. It will be noted that the key actuated mechanism and the knob actuated mechanism operate independently of each other, as is 85 clearly shown in Fig. 2.
- After the door has been again closed, the bolt 18 may be returned to its operative or 90 locking position by again actuating either the key actuated mechanism from the outside or the knob 36 from the inside, as the case may be. These operations will cause either the nose 35 of the lever 26 to engage 95 the cam 49 or one of the noses 40 of the lever 38 to contact with the cam 50, the operation in either case serving to move the shoulder 45 out of the notch 47. The bolt 18 being in 100 this manner released from the locking influence of the locking lever 43, as shown in Fig. 4, will drop by gravity into the notch 22 or 22^a of the coöperating keeper 19 or 19^a to again securely lock the door in its closed 105 position. The return of the bolt 18 to its 110 operative position may be controlled by means of the key 57 or knob 36, or in other words, by causing the pins 34 or 39 of the levers 26 and 38 respectively to exert a restraining action upon the extension 24, as 115 will be apparent.
- It will be noted, when the bolt 18 is in its operative position, that the projecting finger 52 carried by the locking lever 43 by 120 entering the notch 53 or, in the absence of said notch, by abutting against the lever 26, arrests the rotative movement of the latter in one direction, as shown in Fig. 3; similarly the finger 54 carried by the bolt 18 by engagement with the lug 55, arrests 125 the rotative movement of said lever 26 in the opposite direction when said bolt 18 is in its inoperative position, as shown in Fig. 4.

With this construction it is impossible for the lever 26 to be moved out of coöperative relation with said bolt regardless of the position of the latter. The double lever 38 is maintained in proper correlation with the bolt 18 through the medium of the notched spring 41 as shown in Fig. 6.

It will, of course, be apparent that the form of bolt and of its coöperating keeper 10 may be other than as shown and that the same may be adapted for special service without in any way detracting from the efficiency of my improved lock. The latter is extremely efficient in action and is proof 15 against any tampering whereby illegitimate entrance through the door 17 or 17^a may be effected. The construction comprises a minimum of parts of simple form which may be easily and economically produced, so that 20 my improved lock, while it possesses a very high degree of efficiency, is low in cost and not likely to become disarranged in use. The arrangement also does away entirely with the use of gears or toothed segments of 25 any kind and provides a lock in which friction is reduced to a minimum. As before stated, the said lock, in addition to its uses in connection with hinged doors as shown, may also be effectively used in connection 30 with sliding and rolling doors of any description.

Various changes in the specific forms shown and described may be made within the scope of the claims without departing 35 from the spirit of my invention.

I claim:

1. In a lock, the combination of a casing, a bolt pivotally mounted in said casing and permanently extending exteriorly thereof, 40 an extension projecting transversely from said bolt, pivoted means permanently mounted in said casing and normally out of engagement with said extension, said means being arranged to describe a circular path 45 intersecting said extension, means for moving said pivoted means into coöperative engagement with said extension to swing said bolt on its pivot, a locking member pivoted in said casing and coöperating devices 50 on said locking member and said extension whereby said bolt is locked in its operative and its inoperative position.

2. In a lock, the combination of a casing, a pivotally mounted bolt, an extension projecting transversely from said bolt, a plurality of levers independently mounted upon opposite walls of said casing, each lever having a portion normally out of engagement 55 with said extension and arranged to describe a circular path intersecting said extension, a plurality of means operated independently of each other for independently moving said levers into coöperative engagement with said extension to swing said bolt on its pivot, 60 and a device whereby said bolt is locked both

in its operative and in its inoperative positions.

3. A lock comprising a casing, a bolt pivotally carried thereby, a slotted extension on said bolt and a plurality of means mounted 70 on said casing in opposed relation to each other and independently operative and coöperating with said slotted extension to swing said bolt on its pivot.

4. A lock comprising a casing, a bolt pivotally carried thereby, a slotted extension, 75 a plurality of levers movably mounted in said casing, pins carried by said levers and means for operating said levers independently of each other to move said pins into 80 said slotted extension whereby said bolt is swung on its pivot.

5. A lock comprising a casing, a bolt pivotally mounted therein and projecting exteriorly thereof, a slotted extension on said bolt, a lever rotatably mounted in said casing, a pin carried by said lever, means for actuating said lever whereby said pin is moved into said slotted extension to swing the bolt on its pivot, means for locking said bolt 90 against pivotal movement and coöperating devices on said lever and locking means whereby the latter is moved to release said bolt.

6. A lock comprising a casing, a bolt pivotally mounted therein and projecting exteriorly thereof, a slotted extension on said bolt, a lever rotatably mounted in said casing, a pin carried by said lever, means for actuating said lever whereby said pin is 100 moved into said slotted extension to swing the bolt on its pivot, a locking lever in said casing, coöperating means on said locking lever and bolt whereby the latter is locked in its operative and in its inoperative positions 105 and coöperating devices on said rotatable lever and locking lever whereby the latter is moved to disengage said coöperating means and release the bolt.

7. A lock comprising a casing, a bolt pivotally mounted therein and projecting exteriorly thereof, a slotted extension on said bolt, a first lever rotatably mounted in said casing, a pin carried by said lever and coöperating with said slotted extension to 110 swing the bolt on its pivot, a second lever rotatably mounted in said casing and movable independently on said first lever, a plurality of pins carried by said second lever and coöperating with said slotted extension 115 to swing the bolt on its pivot and means for arresting the rotative movements of said levers.

8. A lock comprising a casing, a bolt pivotally mounted therein and projecting exteriorly thereof, a slotted extension on said bolt, a locking lever for locking said bolt against pivotal movement, cams carried by 125 said locking lever, a plurality of independently movable levers in said casing, means 130

for actuating said levers, devices on said levers coöperating with said cams to move said locking lever to an inoperative position and pins on said levers coöperating with said 5 slotted extension to swing said bolt on its pivot.

9. A lock comprising a casing, a bolt pivotally mounted therein and extending exteriorly thereof, a slotted extension on said 10 bolt and provided with spaced notches, a locking lever in said casing, a shoulder carried by said locking lever and coöperating with said notches to lock said bolt respectively in its operative and its inoperative positions, a cam carried by said locking lever, an operating lever, a nose carried by said operating lever and arranged to engage said cam to move said locking lever whereby said shoulder is moved out of said notches to release the bolt, a pin carried by said operating 20 lever and coöperating with said slotted extension to swing the bolt on its pivot, and means for actuating said operating lever.

10. A lock comprising a casing, a bolt pivotally mounted therein and extending exteriorly thereof, a slotted extension on said bolt and provided with spaced notches, a locking lever in said casing, a shoulder carried by said locking lever and coöperating 25 with said notches to lock said bolt respectively in its operative and its inoperative positions, a pair of cams carried by said locking lever, a single lever rotatably mounted in said casing, a device carried by said single 30 lever and arranged to engage one of said cams to move the locking lever to an inoperative position whereby said shoulder is moved out of said notches to release the bolt, a pin carried by said single lever and coöperating 35 with said slotted extension to swing the bolt on its pivot, a double lever rotatably mounted in said casing, a plurality of devices carried by said double lever and arranged to engage the other cam whereby said locking lever is moved to an inoperative 40 position to disengage said shoulder from said notches and release the bolt, a plurality of pins carried by said double lever and coöperating with said slotted extension to swing 45 the bolt on its pivot and a plurality of means for independently actuating said single and double levers.

11. A lock comprising a casing, a bolt pivotally mounted therein and extending exteriorly thereof, a slotted extension on said bolt and provided with spaced notches, a locking lever in said casing, a shoulder carried by said locking lever and coöperating 50 with said notches to lock said bolt respectively in its operative and its inoperative positions, a pair of cams carried by said locking lever, a single lever rotatably mounted in said casing, a device carried by said single 55 lever and arranged to engage one of said cams to move the locking lever to an inoperative

position whereby said shoulder is moved out of said notches to release the bolt, a pin carried by said single lever and coöperating with said slotted extension to swing the bolt on its pivot, a double lever rotatably 60 mounted in said casing, a plurality of devices carried by said double lever and arranged to engage the other cam whereby said locking lever is moved to an inoperative position to disengage said shoulder from 65 said notches and release the bolt, a plurality of pins carried by said double lever and coöperating with said slotted extension to swing the bolt on its pivot, a plurality of means for independently actuating said single and double levers, a stop carried by said locking lever for arresting the rotative movement of said single lever in one direction when the bolt is in its operative position, a stop carried by said bolt for arresting the 70 rotative movement of said single lever in the opposite direction when the bolt is in its inoperative position and a spring coöperating with the pins on the double lever to arrest 75 its rotative movements.

12. A lock comprising a casing, a bolt pivotally carried thereby, locking means for locking said bolt against pivotal movement, rotatable means for releasing said locking 80 means and for swinging said bolt on its pivot, a projection carried by said locking means for arresting the rotative movement of said rotatable means in one direction when said bolt is in its operative position and a projection carried by said bolt for arresting the 85 rotative movement of said rotatable means in the opposite direction when the bolt is in its inoperative position.

13. A lock comprising a casing, a bolt pivotally carried thereby, locking means for locking said bolt against pivotal movement, rotatable means for releasing said locking 90 means and for swinging said bolt on its pivot, and projections carried respectively by said bolt and locking means whereby the 95 rotative movements of said rotatable means are arrested.

14. The combination of a door casing, a door movably mounted therein, a keeper located upon said casing, a lock carried by said door, a pivoted bolt forming part of said lock and arranged to extend in front of said keeper to resist an inward movement of said door, a member on said bolt arranged to extend transversely beyond said keeper to 100 resist a separation of the free vertical edge of said door from the opposed edge of the door casing, and a second member carried by said first member and arranged to extend behind said keeper to resist an outward 105 movement of said door.

15. In a lock, the combination of a casing, a pivotally mounted bolt provided with a slot, a movable lever, a projection carried by said lever permanently mounted on said 110

casing and means for actuating said lever to move said projection into said slot whereby said bolt is swung on its pivot.

16. In a lock, the combination of a casing, 5 a pivotally mounted bolt, a movable lever permanently mounted on said casing, one of said elements being provided with a slot, a

projection on the other of said elements, and means for actuating said lever to bring said slot and projection into coöoperative engagement whereby said bolt is swung on its pivot. ¹⁰

In testimony whereof I have hereunto set my hand.

JACOB KOHN.
